(57) **CLAIM**

The ornamental design for an inflatable floating island, as shown and described.

DESCRIPTION

FIG. 1 is a perspective view of the inflatable floating island showing my new design;

FIG. 2 is an elevational view centered on one of the eight openings in the canopy;

FIG. 3 is a top plan view thereof;

FIG. 4 is a bottom plan view thereof; and,

FIG. 5 is an elevational view centered on the support between two of the eight openings in the canopy.
